United States Patent Office.

EMMONS HAMLIN, OF WINCHESTER, ASSIGNOR TO "MASON & HAMLIN ORGAN COMPANY," OF BOSTON, MASSACHUSETTS.

Design No. 4,161, dated June 21, 1870.

DESIGN FOR AN ORGAN.

The Schedule referred to in these Letters Patent and making part of the same.

To all whom it may concern:

Be it known that I, EMMONS HAMLIN, of Winchester, in the county of Middlesex and State of Massachusetts, have invented or produced an Improved Design for an Organ; and I do hereby declare that the following, taken in connection with the drawings, which accompany and form part of this specification, is a description of my invention sufficient to enable those skilled in the art to practice it.

My invention or new design has particular reference to those instruments of that class of reed musical instruments known as parlor or cabinet organs, in which the reeds, wind-box, key-board, and other parts are enclosed in an upright case extending to the floor; and

My improvement consists in a new form given to said enclosing case, which new form not only imparts elegance to the instrument, but enhances its musical properties.

The new design or form is shown in the accompanying photograph embodied in a Mason & Hamlin organ.

a shows the main part of the case;

b, the front part; and

c, the key-board.

Instead of making the main or rear part of the case

of a length corresponding to the length of the key-board, I extend the opposite ends as seen in the photograph, thereby forming at each end a vertical chamber, *d*, the vertical end panels *e* of the extended chambers connecting with the narrow front of the instrument by inclined panels *f*.

It will be seen at a glance that this improvement adds greatly to the effective appearance of the organ, taking away the crude box-shape which these instruments generally possess, and the vertical spaces at the ends of the organ form two resonant chambers, which improve, to a very marked effect, the tone of the instrument.

The connection between the narrow front and the widened rear and rectangularly-shaped case, may be made by variously inclined panels, my improvement consisting in giving the long and extended form to the rear part of the case, and connecting it with the narrower front part by suitable panel-work.

I claim the new design or form for a cabinet or parlor organ, substantially as shown and described.

Executed May 20th, A. D. 1870.

EMMONS HAMLIN.
